Mar. 696

Joseph W Gardner, of Shelburne Falls, Mass.
Letter Patent No. 696. Dated Mar. 20. 1835

The schedule referred to in these Letters Patent and making part of the same
C^o all whom it may concern.

Be it known that I, Joseph W. Gardner, of Shelburne Falls, in the County of Franklin, and State of Massachusetts have invented or introduced a new and original design for a fork, and I do hereby declare that the following is a full and exact description of the same reference being had to the accompanying drawings, in which —

Fig. 1. is a perspective view.

Fig. 2. a front longitudinal elevation, and

Fig. 3. a side longitudinal elevation.

A. represents the handle of the fork, which handle is made in any of the usual or further forms, and of any suitable material for the same. B. represents an oval concave bolster, which said bolster may also be made in any of the usual or appropriate forms to correspond with the other parts of the fork and handle. — C. represents the neck of the fork, which, arising from the crown of the bolster B. in a form, whose cross section is elliptical, or nearly so, is prolonged longitudinally in nearly the same cross sectional form and at the same time gradually and symmetrically diminishing in both its diameters throughout nearly the entire length of the said neck, and then gradually and symmetrically increasing in its proportions, to properly connect with the shank D. This shank D. arises from the terminus of the neck C. the edges thereof having an internal curvature from its junction with the neck C. to the upper limit of said shank D. where it meets and connects with the bosom E. The bosom E. is in its lateral contours composed of opposite external curvatures or arcs, which, joining with the internal curves of the shank D. constitute a nearly correct "cima reversa" in their lateral contours. The corners of the shank D. and bosom E. are rounded as represented. From the upper or wider extremity of the bosom E. is prolonged the blade or prongs F. of any of the usual proportions and number. In Fig. 3. is represented the curvature or bend of the bosom E. the shank D. and the neck C. forming in their outline a peculiar curvature somewhat resembling the "cima recta" upon its inner, and the "cima reversa" upon the outer side of the same, and the curvature being continued throughout the length of the prongs F. the whole constitutes a new peculiar and symmetrical configuration of the entire Fork.

I do not claim any particular form or proportion of the handle A. nor the bolster B. nor any number or size of the prongs F.; — but what I do claim as my invention or production is the peculiar configuration of the parts C. D. and E. substantially as described and represented in the accompanying drawings.
